10 Claims. (Cl. 260—566)

This invention relates to the production of cycloalkanone oximes by the reduction of cyclic nitro paraffins.

FIELD OF INVENTION

Many processes are known for the reduction of nitro compounds in which amines are obtained. If it is desired to manufacture oximes from the nitro compounds, the reduction process must be carried out in such a manner that oxime is formed as an intermediate reduction product which, under the given reaction conditions, cannot be reduced further to an amine. The reactions involved are represented by the following formula:

wherein R_1 is an organic radical and R_2 is an organic radical or hydrogen.

This type of reaction can be partly attained by reducing the sodium compound of the nitro paraffin with tin or zinc in an acid medium, preferably by means of hydrochloric acid. However, when such a reduction is carried out, only low yields of oxime, about 40 to 50% by weight based on the nitro compound, are obtained, amines and ketones being formed as by-products.

Oximes can also be manufactured by reducing sodium salts of nitro paraffins with hydroxylamine compounds, but in this case, the reduction must be carried out at a low temperature, below 5° C., so that intensive cooling is necessary, and the reducing agent is expensive.

OBJECTS

A principal object of this invention is the provision of new methods for the production of cycloalkanone oximes from nitrocycloalkanes. Further objects include:

(1) The provision of improvements in methods for making cycloalkanone oximes by reduction of cyclic nitro-paraffins.

(2) The provision of new reducing reagents for use in such reactions.

(3) The provision of such reactions which may be carried out at normal temperatures and pressures, thus eliminating need for complex cooling or other complicated apparatus.

(4) The provision of new methods for making cycloalkanone oximes in which the oximes may be produced in relatively high yields.

Still further objects and the entire scope of applicability of the present invention will become apparent from the detailed description given hereinafter; it should be understood, however, that the detailed description and specific examples, while indicating preferred embodiments of the invention, are given by way of illustration only, since various changes and modifications within the

2

spirit and scope of the invention will become apparent to those skilled in the art from this detailed description.

GENERAL DESCRIPTION

5 These objects are accomplished according to the present invention through the reduction of nitrocycloalkanes using a solution of an inorganic sulfide as the reducing agent. Preferably, the nitrocyclohexane, such as nitrocyclohexane, is dissolved in a solvent, such as a lower aliphatic alcohol, to which a solution of inorganic sulfide is added or formed in situ, by the introduction of materials to form an inorganic sulfide, e. g., by the introduction of ammonia and hydrogen sulfide.

10 The success of this invention is due, to a large extent, 15 to the surprising discovery that reduction of nitrocycloalkanes with soluble sulfides leads to the formation of high yields of oximes. This is unique, because the formation of amines, instead of oximes, is to be expected, since it is established practice to employ soluble sulfides as 20 reducing agents in the manufacture of amines from the corresponding aromatic nitro compounds.

25 The manner in which these new discoveries can be utilized and the details of operation, according to the present invention, can be more fully comprehended by reference to the following illustrative examples of actual operations, in accordance with the invention.

Example I

At a temperature of about 100° C. and in the absence 30 of air, 2 gram moles of sodium hydrosulfide are added with moderate stirring to a solution of 1 gram mole of nitrocyclohexane in 2 litres of butanol. After a reaction period of 20 minutes, 55% by weight of the nitrocyclohexane is reduced. The yield of recovered oxime 35 amounts to 95% based on converted nitrocyclohexane.

Example II

In an analogous manner as described in Example I, the reduction is carried out with ammonium polysulfide 40 at a temperature of 70° C., while ethanol is used as a solvent. The yield of oxime corresponds to 95% of the converted initial material.

Example III

Into a solution of nitrocyclohexane in ethanol containing 45 0.1 gram mole of nitro compound per litre, equimolecular amounts of ammonia and hydrogen sulfide are introduced at room temperature. After a reaction period of about 1 hour, 95% of the nitrocyclohexane is reduced to the corresponding oxime.

DETAILED DESCRIPTION

The new procedures are generally applicable to nitrocycloalkanes (also called cyclo nitro paraffins). The examples illustrate the use of nitrocyclohexane for this 55 purpose, but other usable materials include:

Nitrocyclopropane
Nitro-2,5-dimethyl cyclohexane
Nitro-2-methyl cyclohexane
Nitro-4-isopropyl cyclohexane
Nitrocyclopentane
Nitro-2-methyl cyclopentane

The reducing agents employed in the process are soluble, 60 inorganic sulfides, such as the neutral or acid sulfides of the alkali metals, the alkaline earth metals and ammonia. Likewise, the polysulfides of these metals or of ammonia 65 may be used.

The sulfide employed as a reducing agent may be added in a dissolved condition to the nitro compound to be reduced. It is also possible to dissolve the nitro compound 70 in the solvent and to add the sulfide to the resulting solution. Furthermore, the nitro compound may be emulsi-

fied in the sulfide solution. According to the preferred embodiment, equimolecular amounts of hydrogen sulfide and ammonia are passed into an alcoholic solution of the nitro compound in which case the sulfide reducing agent is formed in the reaction mixture. It is also possible to introduce H_2S into a solution of nitrocyclohexane and alkali hydroxide or alkaline earth hydroxide.

The sulfides are employed as a solution preferably in an organic solvent, especially, a lower aliphatic alcohol, e. g., ethyl alcohol, propyl alcohol, or butyl alcohol, but other solvents, such as water, may be used. The proportions of solvent to the reducing agent or, in turn, to the nitrocycloalkane are not critical and ratios of 1 to 10 parts of solvent for each part of sulfide, and 1 to 20 parts of solvent for each part by weight of nitrocycloalkane are representative of preferred ratios.

Preferably, the reaction is carried out at ordinary pressure, since this eliminates the need for complicated apparatus and because the reaction proceeds with very favorable results at these pressures. If it is desired to carry the reaction out at a temperature above the boiling point of the solvent, elevated pressure may be used or suitable condensing apparatus may be employed. It is desirable to carry out the reduction under non-oxidizing conditions in order to avoid oxidation of sulfides, so that a slight over-pressure may conveniently be maintained in the apparatus by means of nitrogen.

The reduction can proceed satisfactorily at room temperature, i. e., about 15° C. , but if more rapid reaction is required, this can be obtained by operating at higher temperatures, for example, 50 to 150° C. , making the preferred temperature range between 15 and 150° C. At these temperatures, the reaction time usually is between 10 and 120 minutes, especially 10 to 60 minutes.

The proportions of sulfide to nitrocycloalkane are not critical and may be varied, although for most desirable results stoichiometric proportions of sulfide or a slight excess thereof, for example, between 2 and 3 moles of sulfide for each mole of nitrocycloalkane, are employed.

Although it is possible for some purposes to use the resulting solutions containing the oxime products without separation of the oxime therefrom, it is generally desirable or necessary to recover the oxime from the reaction liquors. Any known method can be employed for this purpose, such as extraction of the solution with a preferential solvent for the oxime, precipitation of the oxime by addition of incompatible materials, or by evaporation of these solvents subsequent to removal of undesired nonvolatile components from the reaction liquors.

CONCLUSION

A new method for making oximes from the corresponding nitrocycloalkanes in high yields and in an easily conducted manner has been described. The reaction has wide application and may be employed to produce a large variety of oximes of cycloalkanes.

I claim:

1. In a process for the production of cycloalkanone oximes, the step which comprises reducing a nitrocycloalkane with a solution of an inorganic salt of hydrogen sulfide in an inert solvent.
2. In a process for the production of cycloalkanone oximes, the step which comprises reducing a nitrocyclo-

alkane with a solution of an inorganic salt of hydrogen sulfide in an inert saturated, lower aliphatic alcohol.

3. In a process for the production of cycloalkanone oximes, the step which comprises reducing a nitrocycloalkane with a water solution of an inorganic salt of hydrogen sulfide.

4. A process as claimed in claim 1, wherein said reaction is conducted at a temperature between 15° and 150° C.

5. A process for the production of a cycloalkanone oxime which comprises providing a solution of a nitrocycloalkane in an inert saturated, lower aliphatic alcohol, introducing ammonia and hydrogen sulfide into said solution and continuing said gas introduction until said nitrocycloalkane is substantially completely reduced to a corresponding oxime.

6. A process for the production of a cycloalkanone oxime which comprises providing a solution of a nitrocycloalkane in an inert saturated, lower aliphatic alcohol, introducing an inorganic sulfide from the group consisting of alkali metal, alkaline earth metal and ammonium sulfides therein, allowing the admixed material to react at 15° to 150° C. for about 10 to 120 minutes and recovering a cycloalkanone oxime from the reaction mixture.

7. A process as claimed in claim 6, wherein said inorganic sulfide is introduced into said solution by adding hydrogen sulfide and a member of the group consisting of the corresponding alkali metal hydroxide, alkaline earth metal hydroxide and ammonia to the solution.

8. A process for the production of cyclohexanone oxime which comprises forming a solution of nitrocyclohexane in an inert saturated lower aliphatic alcohol, heating the solution to about 70° to 100° C. , adding about 2 moles of an inorganic salt of hydrogen sulfide for each mole of nitrocyclohexane to said solution, allowing the materials to react for about 10 to 60 minutes, and recovering cyclohexanone oxime from the reaction mixture.

9. A process as claimed in claim 8, wherein said alcohol is butanol and said sulfide is sodium hydrosulfide.

10. A process as claimed in claim 8, wherein said alcohol is ethanol and said sulfide is ammonium polysulfide.
